[57] CLAIM

The ornamental design for a hand-held electronic fish scale, as shown and described.

DESCRIPTION

FIG. 1 is a perspective view of a hand-held electronic fish scale showing my new design;

FIG. 2 is the front plan view of the design of FIG. 1;

FIG. 3 is the back plan view to FIG. 1;

FIG. 4 is a side view to FIG. 1, the opposing side view being identical thereto;

FIG. 5 is a top plan view thereof; and,

FIG. 6 is a bottom plan view thereof.

The broken line showing is for illustrative purposes only and forms no part of the claimed design.
